METALLIC PARTITIONING

Alfred B. Bell, Gardner, Mass.

Application October 2, 1936, Serial No. 103,661

25 Claims. (Cl. 189—34)

This invention relates to metallic partitioning and, more particularly, to hollow sectional forms thereof which are adapted for quick set-up, ready change, and expeditious dismantling when necessary or desirable.

An important object of the invention is a novel form of partitioning wherein all the structural parts are mainly composed of sheet metal, and a quick connection is provided whereby the 10 setting-up or dismantling is greatly facilitated.

Another feature of this invention has reference to a novel manner of effecting flush-joining of the panels longitudinally of the posts, whereby the latter are completely concealed when the 15 partitioning is set-up.

A further object of this invention is to provide a hollow sound-proof partitioning, or one in which the posts are effectively insulated against sound conduction as between the spaced 20 panelings.

In addition to the above stated fundamentals, as well as ancillary advantages, this invention involves certain structural details whereby a simple, economically fabricated, and easily set-up 25 or knock-down form of sectional metal-partitioning is provided.

Generally stated, the present invention consists of the novel details of construction, combinations of means and arrangements of parts 30 hereinafter described, illustrated by the accompanying drawings, and more particularly expressed in the claims at the conclusion of this specification.

In the drawings:—

Fig. I is an elevation of sectional metallic partitioning embodying the present invention in one preferred form.

Fig. II is a broken vertical section taken as indicated by the arrows II—II in Fig. I, and 40 drawn to a larger scale.

Fig. III is a similar-scale section on the plane designated III—III in Fig. I.

Fig. IV is a fragmentary sectional view drawn to a larger scale, and looking in the direction of 45 the arrows IV—IV, Fig. I.

Fig. V is a broken horizontal section on the plane marked V—V in Fig. I, and likewise drawn to a larger scale for clarity in showing important structural features.

Fig. VI is a staggered section on the plane designated VI—VI in Fig. I.

Fig. VII is a corresponding section on the plane VII—VII in Fig. I.

Fig. VIII is a fragmentary view, partly in vertical section of a post bottom anchor and shim

arrangement, taken approximately as indicated by the arrows VIII—VIII in Fig. IV.

Fig. IX is a horizontal section on the plane designated IX—IX in the preceding illustration.

Fig. X is a fragmentary perspective view of a 5 preferred type of cornice in accordance with this invention.

Fig. XI is a broken perspective view of one of the posts.

Fig. XII, Sheet 2, is a vertical section taken 10 on the plane designated XII—XII in Fig. VI.

Fig. XIII is a perspective view of a preferred form of anchor element adapted to this invention.

Fig. XIV is a perspective view of a preferred 15 form of post shim for use with the anchor element of the preceding illustration.

Fig. XV is a perspective view of a clip, hereinafter more fully described.

Fig. XVI is a fragmentary perspective view of 20 a modified form of post construction effective to prevent sound conduction between the paralleling panels of the partitioning.

Fig. XVII, Sheet 3, is a fragmentary plan section 25 illustrative of the application of the improved paneling of this invention to the modified form of post construction shown in the preceding figure; and,

Fig. XVIII is a sectional view of a slightly modified form of the cornice structure shown 30 in Fig. X.

In all the views corresponding parts are distinguished by similar reference indicia, with discriminating exponents applied where necessary.

Referring to Fig. I, the reference numeral 1 35 indicates a wall from which a length of the improved partitioning, comprehensively designated 2, extends; said partitioning comprising posts 3, glazed panels 4, solid panels 5, a cornice 6, and door 7, all of sheet metal construction.

The posts 3 are, preferably, of the form best 40 understood from Figs. II—IX, XI and XII, and consist of rectangular section members embodying a main wall 8, spaced walls 9, and confronting edge sections 10 jointly defining a longitudinal gap 11 extending the full length of the post 3 in parallel relation to the main wall 8,

and for a purpose later on explained. The posts 3 are each provided near the top and bottom 45 thereof with laterally projecting pins 12, 13, respectively, drifted, or otherwise retained in register holes 14 through the main wall 8 and confronting edge sections 10; said pins 12, 13

being adapted for engagement by clips 15 provided for the purpose on the respective panels 50 55 55

- 4, 5. Each post 3 is also provided near its bottom with vertically aligned interconnected key-hole orifices 16 in both the spaced walls 9, for a purpose hereafter set forth.
5. In order to rigidly secure the posts 3 to a floor, or the like, and as best understood from Figs. II, IV, VIII and IX, use is made of an anchor-piece 17, Fig. XIII, and a shim 18, Fig. XIV. The anchor-piece 17, Fig. XIII, preferably, comprises a base section 19 having a central orifice 20, and parallel upstanding flanges or tabs 21, with central notches 21' for a purpose later on referred to, said tabs being adapted for snug fitment between the post walls 9, as well as of a width for similar engagement between the post main wall 8 and confronting edge sections 10 thereof, as will be understood from Figs. VIII and IX more particularly. The shim 18, Fig. XIV, embodies a base 22 with an elongated slot 23 therethrough, and upstanding flanges 24 having stepped or serrated inclined edges 25 extending from the high point of said flanges down to low points proximate the entering edge 22' of the shim base 22. It is to be observed the flanges 24 parallel the slot 23 and that they are spaced apart to a dimension materially less than that intervening the flanges 21 of the anchor piece 17; also that the anchor piece 17 and shim 18 are secured in operative relation by suitable hold-down means 30. The upper surfaces of the serrated edges 25 are, preferably, slightly inclined downwardly, relative to the horizontal, in order to prevent any slippage of the shim 18 when forced below the posts 3.
35. Referring again to the clips 15, and as best understood from Fig. XV, each said clip is, preferably, of angular form to provide an attaching part 27 having rounded ends 27' and a clip flange 28, the latter preferably having its ends curved at 40 29, to form lead-in or out camming sections, for coaction with the pins 12, 13 as later on explained. Or the clips 15 may, obviously, be otherwise formed with suitable attaching means, other than the part 27, as may be found expedient or desirable.
45. Each glazed or solid panel 4, 5, respectively and preferably, has both of its sheet metal facing elements 30, Figs. II-VII, laterally extended and retroverted to provide flanking flanges 31, with 50 the inner portion of the retroversion suitably angled at 32 for attachment to the panel body 33, which may be of appropriate insulating material with the facing elements 30 cemented thereto. These angled portions 32 afford means to 55 which the clips 15 are secured, as by spot-welding for example, in positions suitable for coaction with the upper and lower post pins 12, 13, when the panels 4, 5 are inserted by sliding-action into place between spaced posts 3. As the respective 60 panels 4, 5 are slid into position and adjoining relation, it is to be particularly remarked that the confronting edges of the flanges 31 abut centrally of the post spaced walls 9, or medially lengthwise thereof, with a flush fit at 34 and 65 thereby completely conceal the posts 3, when the partition 2 is set up.
- The left-hand solid or wall-abutting panels 5, Figs. I and V, are each provided at one vertical edge only with a flanking flange 31, and at the 70 other vertical edge the sheet metal facing is extended to constitute a plain flange 35, for engagement between the gripping jaws 36, 37 of a wall channel 38. This wall channel 38 is preferably, although not essentially, fabricated of sheet metal to the cross-section shown at the left-hand

side of Fig. V; that is to say, it embodies a web portion having longitudinal stiffening ribs 39, and flanges with their edges inwardly retroverted at 40 to form the gripping jaws 36. Correspondingly the inner flanges 37 of the wall channel 38 are 5 made of sheet metal to provide attaching flanges 41 rigidly secure, as by spot-welds for instance, to said wall channel stiffening ribs 39; and an angled ridge 42 for point contact with the inner surface of the panel flanges 35 in opposition to the gripping jaws 36 aforesaid.

The window-frame jambs or vertical rails 43 of the glazed panels 4 are, preferably, of the cross-section shown in the central portion of Fig. V; that is to say, each jamb 43 is made from sheet 15 metal to provide a rectangular-section rail 44 with an integral facing-flange 45 projecting from one of its corners, for engagement with the partition posts 3. The flange 45 is made by retroversion of part of the sheet metal into meeting relation in 20 the plane of one of the post portion inner or outer walls 9, as clearly understandable by those conversant with the art; while its free edge portion is angled at 45' and to which clips 15 are attached for window-retaining engagement by the projecting ends of the registering partition post pins 12, as hereinbefore described in connection with the respective panels 4, 5. The vertical and horizontal muntin of the windows, respectively comprise opposing substantially closed rectangular-section 30 sheet-metal elements 46, 46' having longitudinal openings 47 in their confronting walls for reception of a connector member 48 of the cross-section shown in Figs. II and V. This connector member 48 is of somewhat hollow-fork cross-section or 35 shaped to define a channel leg-portion 49 having holes at spaced intervals for reception of securing means 50 passed through registering apertures in the rail 46, and said member 48 also embodies outwardly directed angular portions 51 with inclined flanges 52. It is to be noted the angular portions 51 and flanges 52 are of such dimensions as to slidably engage the confronting edges of the openings 47 and the diagonally-opposed inner corners of the rail 46' into which the connector 45 member 48 is first slid; while it will be also understood that when the opposing rail 46 is similarly applied to the channel leg portion 49, and the securing means 50 affixed, the glazing 53 will be properly clamped in place. It is also to be particularly noted that the confronting edges of the rail 46 that define its opening 47 are outwardly angled at 46a for engagement with the leg portion 49 and that the muntin is disposed inside of the parting line so as to facilitate setting-up and 55 dismantling of the glazed panels 4.

The glazed panel window sills are preferably formed, as shown in Fig. II, by extending both sheet metal facing elements 30, of the panels 4, upwards and inwards at 54, then bending the same 60 to form horizontal parts 55, in a common plane, turning one of said parts downwards at 56, and downwardly stepping the opposing part 55 to provide an angular seat 57 for the bottom of the glazing 53. This seat 57 also embodies a flanking 65 runner 58 into which the part 56 snugly fits, as readily understandable on an inspection of Fig. II. The sheet metal window lintel or top 59 is made of a cross-section to provide parallel vertical walls 60, 61 with horizontal flanges 62, preferably having their free edges downwardly angled at 63, for a purpose hereinafter explained. The wall 60 is longitudinally beaded inwardly at 64 to provide a horizontal 65, and the wall 61 is angled at 66 with an inclined portion 67 merging 75

into the lower edge of said wall 61. Adapted for coaction with the horizontal 65 is a glazing retainer 68 of irregular cross-section and embodying a vertical flange 69 with its upper edge inwardly-turned at 70 for engagement below the confronting edge of the horizontal 65 aforesaid, and an inclined flange 71 with its edge inwardly turned at 72, in conformity with the curvature merging from the bead 64 into said horizontal 65.

Attached to the horizontal 65, as by screws 73 for example, is a strip cleat (or a succession of aligned cleats) 74 having the longitudinal edges rounded at 75 for coaction with the edges 70, 72, whereby the glazing retainer 68 is rigidly held in place, in an obvious manner.

Referring now to the cornice 6, as best understood from Figs. II, III and X, the same consists of sheet-metal opposing sections 76 having their upper paralleling edges inwardly lapped at 76' for reinforcing purposes, while the lower edges are correspondingly formed at 77. The opposing sections 76 are also longitudinally and laterally cut out at spaced intervals 78 and are rigidly secured together thereto by brace plates 79, each having an opening 80 for electric light wires and the like, and a plurality of holes 81, for passage of suitable attaching means 82, Figs. II and III, whereby the cornice 6 is secured to opposing horizontal tabs 83 at the top of the posts 3. It is to be noted that the cut-offs 78 and associated brace plates 79 are spaced at predetermined regular intervals, so that provision is made for spacing the posts 3 as desired or found preferable, as well as to accommodate panels 4, 5 of different widths. The material separated by the cut-outs 78 is appropriately formed to provide longitudinal channels 84, 85, into the latter of which the window top flanges 62 of Fig. II, or the panel facing metal top anglings 30' of Fig. III, tightly fit; while the abutting flanges 84' of the channels 84 are preferably spot welded at intervals to prevent their separation and to additionally brace the opposing sections 76. A sheet metal channel 86, is preferably employed to close in the cornice 6 by frictional engagement between the lapped edges 76; said channel having its lower flange-edges turned inwardly at 87 for seating on the cornice brace plates 79, as clearly shown in Figs. II and III.

In order to fit the door 1 into the improved partitioning 2 of this invention, and referring to Figs. I and VI, use is made of hollow sheet metal jambs 88, preferably of the cross-section seen to best advantage in the latter figure. Each jamb 88, it will be observed, embodies parallel facing walls 89, 90 having the longitudinal portions retroverted and confrontingly angled at 91 to provide facing flanges 45 for lapping the posts 3 in the manner hereinbefore described in connection with the panels 4, 5, but, in addition thereto, to abut the main walls 8 thereof as well. The jambs 88, it will also be seen, are suitably fabricated to provide a channeled stop-portion 92, a door edge receiving-section 93, and an angular corner-trim 94. To rigidly brace the jamb walls 89, 90, against expansion or distortion, tie element 91' are used at spaced intervals across the angled parts 91; and for attaching the jambs 88 to the posts 3, use is conveniently made of clamps 95, at suitable intervals between the post pins 12, 13, said clamps bridging the jamb angles 91 and being conveniently secured in place by screw-studs 96, in a manner clearly apparent from Fig. VI; while 97 designates the door hinges.

Returns 98 and "corner-posts" 99, are shown

to best advantage in Fig. VII. Where a return 98 is desired, use is made of a half-post 3' with upper and lower pins 100, with which the return panel flanges 101 engage, as before described in connection with the panels 4, 5, and such half-posts 3' are preferably secured in place by drive screws "S", or other removable means, engaging in the main wall of said half-posts, abutting partition panel flanges 45, and the confronting post 3 spaced wall 9. Each "corner-post" 99 embodies inner and outer sheet metal angular-components 102, 103, respectively; the inner component 102 having its flanges channeled at 104 for support of upper and lower post pins, the latter 13 only being visible in Fig. VII. The outer corner-post component 103, has its flanges retroverted and inwardly angled at 105, for securement thereto of clips 15 whereby said component is held in engagement with the inner projecting ends of the pins 13, as clearly understandable from an examination of Fig. VII; while the connected panel 5, for example, is of the type previously described, hence corresponding reference characters are employed to obviate repetitive explanation. The inner component 102 of the corner post 99 is also longitudinally stepped or angularly-grooved at 106 for abutting reception of the inner corner panel flanges, pins 13' being provided for engagement by the clips 15 on said flanges, in accordance with the preceding disclosure.

For sustaining the several panels 3, 4 at their lower edges, in spaced relation to the floor level, use may be made of sheet metal channel supports 107, preferably of the cross section best shown in Fig. II, said supports embodying gutters 108 flanking their flanges 109 on the inside for reception of base flanges 110 formed of the panel facing elements 30, similar to the side flanges 45, hereinbefore explained. These supports 107, in turn, rest at their extremities upon angle brackets 111 secured by bolts 112, studs or other suitable means, to the post edge sections 10, in an obvious manner.

Floor trim or "mop stripping" 113, likewise made of sheet metal, is applied to either or both sides of the partitioning 2, said stripping having its lower portion retroverted into mutual contact at 114, and being provided with opposed grip tongues 115, at intervals of its length, for frictional engagement with the inner confronting faces of the upstanding flanges 45 of suitable channels 30 rigidly secured to the floor intermediate the anchor-pieces 17. The upper portion of the mop stripping 113 is spacially retroverted at 116 for snug engagement between the panel facing elements 30 and the support flanges 109. Plinth pieces 117, preferably, consisting of sheet metal slabs having the upper edge inwardly angled at 118, for contact with the panel facing elements 30, are provided in conjunction with the partitioning posts 3, said plinths 117 being conveniently held in place by headed studs 119, projecting therefrom, passing through the key-hole orifices 16 and snugly engaging against the inner face of the post spaced-walls 9.

In some instances the anchor piece notches 21 are designed to clear the lower plinth studs 119, when it is desirable said flanges project upwardly well within the posts 3; or the mop-stripping 113 is of a shorter vertical height with the studs 119 correspondingly allocated to a lower level and closer spacing; or the key-hole orifices 16, are allocated to a low level as indicated in Fig. XI.

Apertures 120, Figs. II and IV more particularly, are provided wherever desirable through

out the length of the posts 3 for entry of electric wiring and so forth; while posts end cut-outs 121, Fig. XI, may be provided for coaction with the top edge of the shim flanges 24, in an obvious manner, if deemed advisable or expedient. Furthermore, when the use of shims 18 is found unnecessary, the posts 3 will seat on the anchor pieces 17, as readily understood by those acquainted with sheet metal constructional-work; 10 while the partitioning 2 may be surmounted by a grille 122, Figs. I, II and III, left open, or be closed to ceiling level as desired.

123, Fig. III, indicates spaced holes in the post main wall 8 for free passage of the screw studs 96 into the clips 95; and 124 designates associated elongated intervening openings whereby finger access can be had to the clips 95 for positioning where desired, above or below the openings 124.

20 Referring now to Figs. XVI and XVII which show a modified form of post 3a, it will be noted the same comprises opposed channels 125, which are permanently united by connector elements 126 and rivets 127, for example, intermediate 25 spacedly-confronting flanges 128 of said channels, with intervening strips 129 of appropriate insulating material. It is also to be particularly observed that the connector elements 126 are of a width less than that intervening the web portions of the channels 125 to afford clearances 130; also that said elements and the insulation strips 129 are notched out at 131, 132, respectively, in order to clear the pins 12 or 13 and eliminate metal to metal sound conduction between the several parts of the post 3a; as well as sound conduction across the panel hollows or between the facing elements 30, in an obvious manner.

40 In Fig. XVIII is shown a slight modification of the cornice 6 wherein the flanges 84' of the elements 16 are spaced apart with an intervening strip 84" of insulating material, and said flanges are connected together by securing means 84"" in an obvious manner, to prevent sound conduction therebetween.

45 Briefly stated, a partition 2 in accordance with this invention is set-up in the field as follows. Assuming the required door jambs 88 to be first secured to the associated posts 3 or 3a by passing the clamp plates 95 through the post openings 50 124 and threading the screw-studs 96 thereinto, in an obvious manner, the procedure is as follows. The anchor-pieces 17 and shims 18 being first placed in position and the hold-down means 55 26 applied, the respective posts 3, "corner posts" 99, and door frame posts 3, 88 are consecutively set-up with application of the intervening panels 5, 4 and 5 and engagement of the clips 15 with the post pins 12, 13. It will now be understood 60 that after each such panel at one side of the partition 2 is put in place the flanking posts 3 and 99, or succeeding posts 3 and 3, 88 are vertically adjusted plumb and to a common height, by the shims 18 when the hold-down means 26 are 65 tightened-up. After each panel 5, 4 at one side of the partition is set-up, and the adjustments made, as just described, the opposing panel 5, 4 is inserted by movement upwardly and downwardly to bring the clips 15 into engagement 70 with the associated pins 12, 13, whereupon the successive panels 4, 5 are correspondingly erected until the partition is complete, whereupon the cornice 6 and grille 122—if used—are applied as hereinbefore disclosed; when the door 7 is hung. 75 From the foregoing the erections of a return 98

will be well understood without further elaboration herein.

The foregoing completes a description of the fabrication and manner of assembly in the field of preferred embodiments of this invention, but it is to be expressly understood no limitation to the precise form and details herein disclosed is intended; inasmuch as various changes, omissions and substitutions, may be made without departing from the spirit and scope of said invention, as more concisely defined by the following claims.

Having thus described my invention, I claim:

1. Partitioning comprising posts having spaced longitudinal faces, panels with facing elements extended therebeyond and retroverted to form flanges for mutual edge abutment medially lengthwise of the post spaced faces, means for securing the panels between the posts by relative sliding action, and means for anchoring the posts in position including coactive shims having portions inclined to the horizontal whereby the posts are vertically adjustable.

2. Partitioning comprising posts having parallel longitudinal faces, hollow panels with facing elements extended and retroverted to form side flanges for mutual edge abutment medially lengthwise of the post parallel faces, means for securing the panels between the posts by relative sliding action, and means for anchoring the posts in position including coactive shims embodying inclined portions whereby the posts are vertically adjustable, in combination with mop-stripping having gripping tongues for engagement with the flanges of channels secured to the floor intermediate the anchoring means.

3. Partitioning comprising sheet metal posts having flat faces, spaced pins projecting in planes parallel to the post flat faces and panels with sheet metal facings laterally extended and retroverted to form flanges for mutual edge abutment medially lengthwise of the post flat faces, said retroversions having the inner portions suitably angled for overlap attachment to the proximate edges of the panel body, and clip means for securing the panel flanges to the pins aforesaid.

4. Partitioning as defined in claim 3 wherein the clip means are of angular form, one flange with rounded end edges and serving for attachment to the panel facing inner angled portions, and the other flange having outwardly curved ends for lead-in or out camming coaction with the post projecting pins.

5. Partitioning comprising sheet metal posts having opposing flat faces, spaced pins extended therethrough to provide projecting ends in planes parallel to said flat faces, panels with sheet metal facings laterally extended and retroverted to form side flanges for mutual edge abutment medially lengthwise of the post flat faces, the retroversions having their inner portions formed for edge overlap attachment to the panel body proximate edges, means for securing the panel flanges to the posts by sliding action, and means for anchoring the posts in vertical position including shims with serrated inclined edges whereby the posts are vertically adjustable, in combination with mop-stripping having grip tongues for clamping engagement over the upstanding flanges of channels secured to the floor intermediate the anchoring means.

6. Partitioning comprising sheet metal posts having opposing flat faces; spaced pins passed through the posts to provide projecting ends in planes parallel with said flat faces; panels having sheet metal facings extended and retroverted

- to form side and bottom flanges, the side flanges being adapted for mutual edge abutment medially lengthwise of the post flat faces, the retroverted bottom flanges being suitably shaped for 5 edge overlap of the confronting panel body portion, and the top facing extension being angled downwardly over the panel body; means for securing the panel side flanges to the post pin ends by sliding action; and sheet metal anchorages 10 with upstanding flanges for securing the posts in vertical position including shims embodying serrated inclined-edges whereby the posts are vertically adjustable; in combination with sheet metal mop-stripping having tongues for engagement over the upstanding flanges of floor channels 15 between the anchorages and snug engagement with the panel facings aforesaid; and sheet metal plinths for application over the mop-stripping ends and removable connection to the posts.
- 20 7. Partitioning comprising sheet metal posts having opposing flat faces and inwardly-directed tabs at their upper ends, spaced pins passed through the posts to provide projecting ends in planes parallel to the flat faces; panels having sheet metal facings extended and retroverted to 25 form side and bottom flanges, the side flanges adapted for mutual edge abutment medially lengthwise of the post flat faces, retroverted bottom flanges suitably shaped for edge overlap with 30 the confronting panel body portion and the top facing extension being angled downwardly there-over; sheet metal channels embodying gutters flanking their side flanges for supporting the panels intermediate the posts in spaced relation 35 to floor level; means securing the panel side flanges to the post pin ends by sliding action; sheet metal anchorages embodying upstanding flanges with associated shims, said shims having serrated inclined-edges for respectively securing 40 and adjusting the posts in vertical position; sheet metal mop-stripping having spacial upper retroversions for engagement in the channel support gutters, and grip tongues engaging over the up-standing flanges of floor channels intermediate 45 the anchorages; and sheet metal plinths over the mop-stripping ends and removably attached to the posts by pin-and-slot connection; in combination with a sheet metal cornice comprising opposed sections, each of which embodies an inverted channel portion seating on the panel upper edge, and intervening brace plates permanently securing the opposed cornice sections 50 together and for attaching said cornice to the post tabs.
- 55 8. In partitioning as defined in claim 7, the combination of posts each of which is of rectangular cross section to include a main wall, spaced panel engaging walls with confronting portions paralleling the main wall to jointly define 60 a gap extending the full length of the post, said post having at the top end inwardly-directed horizontal tabs, and key-hole orifices in the spaced walls proximate the post lower ends.
9. In partitioning as defined in claim 7 the 65 combination of posts each of which comprises opposed channels, a connector element intermediate confronting flanges of said channels, strip insulation between said flanges and the connector element, and means permanently securing said 70 parts together.
10. In partitioning as defined in claim 7 the 75 combination of posts each of which comprises opposingly-directed channels; a connector element intermediate planarly-related flanges of said channels and of less width than that interven-

ing their web portions; strip insulation between the channel flanges and the connector confronting edge portions; means permanently securing the channel flanges, strip insulation and connector together; pins projected through the 5 channel flanges; and notchings in the strip insulation and connector edges defining clearance about the said pins.

11. In partitioning as defined in claim 7, the combination of post anchorages each of which embodies a base section with an orifice therethrough for passage of appropriate securing means, and parallel upstanding flanges for engagement between the inner ends of the post flat-face portions. 15

12. In partitioning as defined in claim 7 the combination of post anchorages each of which embodies a rectangular base section with an orifice therethrough for passage of suitable securing means, parallel upstanding flanges of narrower 20 width than the base for engagement between the inner ends of the post flat-face portions, and notches in the upper edges of said flanges for the purpose specified.

13. In partitioning as defined in claim 7 the combination of post shims each of which embodies a rectangular base with an elongate slot therethrough; upstanding inclined flanges along parallel sides of the base, of a spacial dimension for clear passage between the anchorage flanges, 30 and said flanges having their inclined edges serrated. 25

14. In partitioning as defined in claim 7 the combination of post anchorage shims each of which embodies a rectangular base with an elongate slot therethrough; upstanding inclined flanges extending along parallel sides of the base, of a spacial dimension for clear passage between the anchorage flanges, and said flanges having their inclined edges serrated, with the serrated 40 edges of one flange opposingly beveled to those of the other flange. 35

15. In partitioning as defined in claim 7 the combination of mop-stripping consisting of sheet metal having the lower edge retroverted and provided with grip tongues effective downwardly to engage the upstanding flanges of the floor channel, and the upper edge of said stripping being retroverted into paralleling relation therewith. 45

16. In partitioning as defined in claim 7 the combination of panel supports each of which consists of an inverted sheet metal channel-section intervening the respective posts, said section embodying gutters flanking its flanges for snug 55 reception of the panel lower edge flange and seating at its ends on angle-brackets secured to the posts.

17. In partitioning as defined in claim 7 the combination of plinths, each of which consists of a rectangular sheet metal slab with the upper 60 edge angled for engagement with the panel facing, and said plinths having headed projections for passage through key-hole slots in the post and gripping engagement with the inner faces of said post spaced walls. 65

18. In partitioning as defined in claim 7 the combination of a cornice consisting of opposed sheet metal elements with the free edges inwardly lapped, one of said edges being formed to channel-section for seating on the panel upper edges, 70 spaced braces permanently securing the opposed elements in parallelism, and said braces being adapted for attachment to the post upper end inwardly directed tabs. 75

19. In partitioning as defined in claim 7 the

- combination of a cornice comprising opposed sheet metal elements with the longitudinal edges inwardly lapped, one of said edges of each element being formed to inverted channel-section 5 for seating on the panel upper edge, spacer plates at intervals permanently securing the opposed cornice elements in parallelism, each said plate being centrally apertured and adapted for attachment to the post upper end inwardly-directed 10 tabs, and a sheet metal channel-section closure frictionally engaging between the opposed elements of the cornice, said closure having its lower edges inwardly shaped to seat on the inverted channel-section portions of the cornice elements. 15 20. In partitioning as claimed in claim 7 the combination of hollow door jambs formed of sheet metal to include parallel facing walls with the longitudinal edge portions retroverted and confronting-angled to provide facing flanges for engagement with the post flat faces, the confronting-angled portions being secured together at intervals by permanently-affixed tie elements to prevent expansion or distortion, said jambs having the intervening portion suitably shaped to 25 provide a channeled stop section longitudinally thereof, a door edge receiving section, and an indented angular corner-trim; and means for securing said jambs to the partitioning posts. 21. In partitioning as claimed in claim 7 the 30 combination of corner posts, each said post comprising inner and outer sheet metal angular components, the inner component having its ridge inwardly-grooved and the flange edges channeled; and the outer component having its flange edges 35 retroverted and inwardly-angled for engagement with the inner component channel webs; and means whereby said corner post components are connected together and to the partitioning panels. 22. In partitioning as defined in claim 7 the 40 combination of a cornice comprising opposed angular-section sheet metal elements, one angular portion having the longitudinal edge inwardly lapped and the other portion being formed to parallel channel sections with the flange adjoining the first mentioned angular portion relatively 45 lapped inwards, sheet metal braces permanently securing said elements together in parallelism and affording attaching means for the post tops, and means uniting the inner confronting channel flanges in abutting relation. 5 23. In partitioning as defined in claim 7 the combination of a cornice comprising opposed angular-section sheet metal elements, one angular portion having the longitudinal edge inwardly lapped and the other portion being formed to 10 parallel channel sections with the flange adjoining the first mentioned angular portion relatively lapped inwards, sheet metal braces permanently securing said elements together in parallelism and affording attaching means for the post tops, insulating means intervening the inner confronting channel section flanges, and means securing the opposing angular section elements permanently together through the said confronting flanges and 15 insulating means. 20 24. Partitioning comprising sheet metal posts having flat faces, spaced pins projecting from said posts in planes parallel to their flat faces, panels with sheet metal facings laterally extended and retroverted to form flanges for edge abutment 25 lengthwise of the post flat faces, and said panels having lateral clips each of which has curved ends with an intervening part for engagement inwardly of the pin projections. 25. Partitioning comprising posts having parallel longitudinal faces, solid and glazed panels with facing elements laterally extended and retroverted to form side flanges for mutual edge abutment medially lengthwise of the post parallel faces, means for securing the panels between 30 the posts by relative sliding action, and means for anchoring the posts in position including co-active shims having serrated-edge inclined-flanges whereby the posts are longitudinally adjustable, in combination with mop-stripping 35 having grip tongues for engagement with the upstanding flanges of suitable channels fixed to the floor intermediate the anchoring means. 40
